(57) CLAIM

The ornamental design for a handheld drug delivery device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view showing a new design for a handheld drug delivery device;

FIG. 2 is a front view of the handheld drug delivery device of FIG. 1;

FIG. 3 is a rear view of the handheld drug delivery device of FIG. 1;

FIG. 4 is a right-side view of the handheld drug delivery device of FIG. 1;

FIG. 5 is a left-side view of the handheld drug delivery device of FIG. 1;

FIG. 6 is a top view of the handheld drug delivery device of FIG. 1;

FIG. 7 is a bottom view of the handheld drug delivery device of FIG. 1;

FIG. 8 is a perspective view of the handheld drug delivery device of FIG. 1 with its cap removed;

FIG. 9 is a perspective view showing a second embodiment of the new design for a handheld drug delivery device;

FIG. 10 is a front view of the handheld drug delivery device of FIG. 9;

FIG. 11 is a rear view of the handheld drug delivery device of FIG. 9;

FIG. 12 is a right-side view of the handheld drug delivery device of FIG. 9;

FIG. 13 is a left-side view of the handheld drug delivery device of FIG. 9;

FIG. 14 is a top view of the handheld drug delivery device of FIG. 9;

FIG. 15 is a bottom view of the handheld drug delivery device of FIG. 9; and,

FIG. 16 is a perspective view of the handheld drug delivery device of FIG. 9 with its cap removed.
